PROCESS OF MAKING FUEL-BRIQUETS.

1,029,022.

Specification of Letters Patent. Patented June 11, 1912.

Application filed October 12, 1910. Serial No. 586,678.

To all whom it may concern:

Be it known that I, ARDON M. MITCHELL, a citizen of the United States, residing at Flushing, in the county of Queens and State 5 of New York, have invented new and useful Improvements in Processes of Making Fuel-Briquets, of which the following is a specification.

This invention relates to certain new and 10 useful improvements in processes of making fuel briquets and the primary object of the invention is to provide for the manufacture of fuel briquets by a process which renders them immediately available for use after 15 completion, without first being aged.

In the drawings: Figure 1 is a side elevation partly in section of an apparatus designed to practice the present invention, and Fig. 2 is a top plan view.

20 In carrying out the process, a base is employed which may be composed either of coal dust, or what is commercially known as "coke breeze", or it may be constituted of a combination of the two in which event 25 from 5 to 10% of coke breeze is used with the remainder of the base composed of coal dust. The mass composing the base is then mixed with a colloidal solution, such as silicate of soda or potash, to render it cohesive. 30 This mass is placed in a hopper 1, which communicates with and is supported by a cylinder or barrel 2. The cylinder is supported by and suitably secured to standards 3, and has an internal diameter and cross 35 sectional configuration to correspond to the diameter and contour of the completed briquets.

Within the interior of the cylinder 2, works a reciprocating piston 4, having suitable packing 5, and bearing a cut off plate 6, at its top, the purpose of which plate is to close the outlet of the hopper, at the point where same communicates with said cylinder. The rod 7, of the piston 4, is connected at its outer end to a sliding guide 8 which reciprocates with the piston in the cylinder. A connecting rod 9, is pivoted to the guide 8, at its inner end, and at its outer end is pivoted to a disk 10, carried on a 45 drive shaft 11. Shaft 11, is suitably driven, as by a drive wheel 12, and belt 13. Disk 10 has a series of apertures 14 therein which are located at different distances from the center of the disk, in order to allow the extent of throw or the length of the distance

traveled by the piston to be varied as desired, in an obvious manner.

Located to one side of hopper 1, is a tank 15, containing a crystallloid solution, a pipe 16, leading from the tank and into cylinder 2 to the front of hopper 1. A rotary valve 17, is located in pipe 16, and has a stem 18, to which is rigidly secured a vertical arm 19. Arm 19 is operated through the medium of a connecting rod 20, pivoted at one end thereto and at its opposite end being connected to a crank 21 on the drive shaft 11, by virtue of which the rod is given a reciprocating movement.

The crystallloid solution, contained in tank 15, may be calcium chlorid or magnesia, which will at once react upon the soluble silicate. As a result of this reaction, calcium silicate is precipitated out, forming a superficial coating on the compressed mass. Dialysis then begins, the calcium chlorid passing through the above mentioned coating and reacting on the colloid, i. e., the silicate of soda or potash forming calcium silicate and chlorid of soda or potash. This chlorid passes out by exosmosis into the calcium chlorid solution. The above reactions will have the effect of causing a cohesion of the neutral particles by crystalline cementation thereof. A portion of the mass of carboniferous matter saturated with a colloidal solution as above described, will, on the return or idle stroke of the piston, fall into the cylinder or barrel 2, since the cut-off plate 6, which virtually forms a bottom for the hopper at that time be withdrawn from its normal or closed position, at the same time the rod 20 moving synchronously with pitman rod 9, rocks arm 19, and thereby the rotary valve 17, opening the latter and allowing the solution in tank 15, to flow into cylinder 2, through pipe 16, the fluid being disposed between the mass which has just entered the cylinder 2, and the previously formed briquet marked A in the drawings.

On its working or return stroke the piston compresses the mass which has just entered the barrel 2, causing the crystallloid solution to saturate the mass, and, in cases where sufficient solution has been admitted to the barrel, the mass will force the solution to assume the form of a body of liquid as depicted at B in the drawings. In the case last noted the opposite faces of the formed briquets, it will be seen, are main-

tained in contact with the solution until the discharge end of the barrel is reached, the completed briquets in the barrel being moved progressively at intervals determined by the length of time elapsing between the working strokes of the piston. Obviously by varying the length of the piston stroke, the thickness of the briquets will be accordingly varied. It will thus be seen that in 10 the course of travel of the briquet through barrel 2, ample time is given the crystalloidal solution to penetrate and harden the briquets, this hardening being an obvious desideratum, since it prevents disintegration 15 both in handling and during combustion. The chemical reaction which sets in results in the formation of a coating of silicate of calcium on opposite sides of each briquet through which chlorid or sodium passes out 20 by exosmosis, which will cause the briquets to separate upon reaching the end of the barrel, in cases where the briquets are brought into contact with each other in their passage through the barrel as distinguished 25 from their separation by the bodies of liquid. Obviously the briquets in passing through the barrel will contact, in cases where by design or otherwise, but a small quantity of the crystalloidal solution is admitted at each retrograde or idle stroke of 30 the piston, or where the briquets absorb the solution in their passage through the barrel prior to reaching the discharge end thereof.

The object of providing a base composed 35 of coal dust and coke breeze is to render the briquet more concrete by filling the voids with abrasive material and by increasing the tensile strength of the briquet to withstand rough usage and handling.

40 It will be obvious that by pivoting the front end of the rod 20 in the different perforations provided for this purpose, in the arm 19, that the throw of the rotary valve

17 will be varied, thus permitting control of the amount of crystalloidal solution 45 which is admitted into the barrel. It will furthermore be seen that the adhesive properties of the colloidal solution with which the base is saturated will, when the briquets are formed therefrom, cause the latter to adhere to the interior of the barrel 2, thus setting up resistance to the passage of the formed briquets through the barrel, thereby providing a substantial rigid surface against which the piston compresses the charge of 50 the base admitted into the barrel. The filling of the voids with coke breeze increases the thermal value of the briquets, and offsets the antagonistic thermal properties of the inorganic binder. 55

60 What is claimed is:

1. A process of making fuel briquets which consists in mixing a colloidal solution with a carboniferous base to cause cohesion of the particles thereof, forming the mass 65 thus treated into a row of successive briquets and simultaneously moving said row in one direction, and introducing bodies of crystalloidal solution between successive briquets during their formation. 70

2. A process of making fuel briquets which consists in mixing a liquid binding agent with a suitable basic mass, forming the mass thus treated into a row of successive briquets, and introducing a hardening 75 agent in a liquid state between each completed briquet and the succeeding briquet before the formation of the latter has been completed.

In testimony whereof I have hereunto set 80 my hand in presence of two subscribing witnesses.

ARDON M. MITCHELL.
